UNITED STATES PATENT OFFICE

106,028

DESIGN FOR A TANK BODY

Benjamin F. Fitch, Greenwich, Conn.

Application October 8, 1936, Serial No. 65,204

Term of patent 7 years

To all whom it may concern:

Be it known that I, Benjamin F. Fitch, a citizen of the United States, residing at Greenwich, in the county of Fairfield and State of Connecticut, have invented a new, original, and ornamental Design for a Tank Body, of which the following is a specification, reference being had to the accompanying drawing, forming a part thereof.

In the drawing, Fig. 1 is a perspective view of

the tank body; Fig. 2 is a side elevation looking at either side, and Fig. 3 an end view looking at either end.

The dominant feature of my design resides in the skirt portion, substantially as shown.

I claim:

The ornamental design for a tank body substantially as shown and described.

BENJAMIN F. FITCH.
